TANK CLEANING MACHINE

Maurice E. Metcalf and Angelas Manuel,
Port Arthur, Tex.

Application January 6, 1953, Serial No. 329,766

3 Claims. (Cl. 299—69)

1

This invention relates to a cleaning machine, and more particularly to a machine for cleaning tanks.

The object of the invention is to provide a tank cleaning mechanism which utilizes revolving water discharge nozzles to effectively clean and remove dirt or other foreign matter from tanks and the like.

Another object of the invention is to provide a tank cleaning mechanism which includes water nozzles that are revolved by the action of the water passing therethrough, there being an adjustable brake mechanism which can be adjusted to control the speed of rotation of the nozzles.

A further object of the invention is to provide a tank cleaning mechanism which is extremely simple and inexpensive to manufacture.

Other objects and advantages will be apparent during the course of the following description.

In the accompanying drawings, forming a part of this application, and in which like numerals are used to designate like parts throughout the same:

Figure 1 is a front elevational view of the tank cleaning mechanism, constructed according to the present invention.

Figure 2 is a rear elevational view of the tank cleaning mechanism of the present invention.

Figure 3 is a fragmentary top plan view of the tank cleaning mechanism.

Figure 4 is a sectional view taken on the line 4—4 of Figure 1.

Figure 5 is a sectional view taken through the nozzle on the line 5—5 of Figure 4.

Figure 6 is a fragmentary elevational view showing a modified arrangement wherein a ratchet is provided for causing rotation of the nozzle support instead of the gear means, the brake features being omitted from this showing.

Figure 7 is a view of the assembly shown in Figure 6 but taken at right angles thereto.

Figure 8 is a view showing the ratchet assembly of Figure 6.

Figure 9 is a sectional view taken on the line 9—9 of Figure 6.

Referring in detail to the drawings, the numeral 20 designates a tube which is adapted to be connected to a hose or pipe 21 as by a threaded connection. The pipe 21 may lead from a suitable source of supply of fluid, such as water under pressure. The tube 20 is provided with an annular flange 22, Figure 4, and the flange 22 terminates in a down hanging annular collar 23. Arranged contiguous to the lower edge of the collar 23 is a stationary beveled gear 24. In-

terposed between the beveled gear 24 and the flange 22 is a thrust washer 25, and the washer 25 is secured to a rotary sleeve 27 by means of pins 26.

5 The sleeve 27 is provided with a pair of diametrically opposed openings 28, and rotatably mounted in the openings 28 is a neck 29, there being bearings 30 for rotatably supporting the neck 29. The neck 29 is provided with a plurality of spaced apertures 33 for the egress therethrough of water, whereby water or other fluid can pass from the pipe 21, through the tube 20, then through the sleeve 27, then through the apertures 33 and into the inside of the neck 29.

10 Extending from the neck 29 and formed integral therewith or secured thereto is a pair of diametrically opposed nozzles 31 which are each provided with an aperture or opening 32 therein for the passage therethrough of water.

15 Connected to an end of the neck 29 is a beveled gear 34 which meshes with the beveled gear 24. A pin 35 has one end arranged in engagement with the beveled gear 34, and the pin 35 includes a portion which extends through a slot 38 that is arranged in a bracket 43. Arranged in spaced relation below the bracket 38 is a block 39, and a stem 40 has its lower end arranged in engagement with the block 39. The stem 40 extends through a piston or plunger 42 which is reciprocably arranged in a cylinder 41. The cylinder 41 is arranged contiguous to or formed integral with a tank or compartment 36, and the tank 36 acts as a reservoir for fluid, the tank 36 being separated from the upper portion of the sleeve 27 by means of a wall 37.

20 The upper end of the stem 40 is arranged in engagement with the bracket 43. A pair of spaced parallel rods 44 have their lower ends extending through the block 39, while the upper portions of the rods 44 slidably project through the bracket 43. It will be noted that the beveled gear 24 is connected to the flange 22 and collar 23 by suitable screws 45.

25 A pair of spaced parallel securing elements 46 which may be nuts, are arranged on opposite sides of the plunger 42, so that as the stem 40 moves up and down the plunger or piston 42 will likewise be reciprocated in the cylinder 41. A conduit 47 has one end connected to the bottom of the tank 36, while the other end of the conduit 47 is connected to the lower end of the cylinder 41, there being a check valve 48 positioned in the end of the conduit 47 which is contiguous to the cylinder 41. This check valve 48

serves to permit fluid to pass from the tank 36 to the cylinder 41 as needed and also serves to prevent the fluid from flowing in the opposite direction from the cylinder 41 to the tank 36.

A tube 49 is arranged in communication with the tank 36, and a check valve 50 is positioned in the tube 49, the check valve 50 serving to permit air to flow into the tank 36 as the fluid is withdrawn therefrom.

A conduit or tube 53 has one end communicating with the upper end of the cylinder 41, while the other end of the conduit 53 communicates with the lower end of the cylinder 41. A valve 51 is interposed in the conduit 53, and a manually operable body member 52 is arranged in threaded engagement with the valve 51. Thus, by adjusting the position of the body member 52 in the valve 51, the size of the orifice or opening in the valve 51 can be regulated so that the passage of fluid through the cylinder 41 can be controlled so that the piston 42 acts as an adjustable brake mechanism to control the rate of rotation of the nozzles.

Referring to Figures 6, 7, 8 and 9 of the drawings, there is shown a modified arrangement wherein instead of using the intermeshing beveled gears to cause rotation of the neck, there is provided a ratchet assembly. Thus, there is provided the tube 20 which can be connected to a suitable source of fluid under pressure, and securing elements such as screws 45 again extend through the collar 23. Instead of using the gear 24 however, a ratchet wheel 54 is secured to the collar 23 by means of the screws 45. A pawl 55 is arranged in engagement with the teeth of the ratchet wheel 54 and a spring member 56 serves to urge the pawl 55 into engagement with the teeth of the ratchet wheel. An arm 57 is connected to the pawl 55 and the arm 57 is connected to an end of a shaft 58. A body member 59 is connected to the shaft 58, and a shaft 60 extends from the body member 59. A roller 61 is mounted on an end of the shaft 60, and the roller 61 is urged into engagement with a cam 63 by means of a spring 62. The cam 63 is secured to an end of the neck 29, and the cam 63 is used in lieu of the previously described beveled gear 34. The neck 29 again has projecting therefrom the diametrically opposed nozzles 31.

The present invention is especially suitable for cleaning tanks, but it is to be understood that the present invention can be used for cleaning other objects as well. In use, the mechanism is arranged contiguous to the portion of the tank to be cleaned. The tube 20 can be connected to a suitable source of fluid under pressure, as for example water, and the tube 20 will convey the water to the sleeve 27. From the sleeve 27, the fluid passes through the openings 33 and into the neck 29 and from the neck 29 it passes through the nozzles 31 and out through the openings 32. This causes the nozzles 31 to rotate due to the jet reactive force of the water issuing from the openings 32. As the nozzles 31 rotate, they cause rotation of the neck 29 and it will be noted that the beveled gear 34 is secured to the neck 29. The beveled gear 34 meshes with the stationary beveled gear 24 so that not only do the nozzles 31 rotate in a vertical plane, but also the nozzles 31 and neck 29 are caused to travel in a horizontal plane. Thus the entire surface of the tank is thoroughly cleaned by the issuing jets of fluid.

Simultaneously, the pin 35 is moved by the gear 34 to which it is attached, and as the pin 35 moves it raises and lowers the stem 40. As the

stem 40 moves up and down it carries the piston 42 therewith so that the hydraulic fluid above and below the piston 42 is constantly worked on. This acts as a brake mechanism whereby the speed of rotation of the nozzles can be accurately controlled. The tank 36 acts as a reservoir to supply hydraulic fluid to the cylinder 41 and by adjusting the body member 52 in the valve 51 the rate of flow of fluid through the conduit 53 can be accurately controlled so that the speed of rotation of the nozzles 31 in a horizontal and vertical plane can be regulated as desired.

In using the arrangement shown in Figures 6 through 9, the ratchet assembly is used in lieu of the intermeshing gears to cause rotation of the nozzles 31 in a horizontal plane. Thus, as the nozzles 31 rotate due to the issuing jets of water, the neck 29 is rotated and this causes rotation of the cam 63. Then, the rotation of the cam 63 causes in and out movement of the roller 61 and this in turn is imparted to the pawl 55 which engages the teeth of the ratchet wheel 54 to cause simultaneous rotation of the nozzles 31 in a horizontal and vertical plane.

The present invention is adapted to be used for cleaning objects such as tanks by means of water. The jet pressure of the water leaving the openings 32 in the nozzles 31 is sufficient to turn the neck 29 which is rotatably mounted in the sleeve 27. The gear 24 is stationary so that as the neck 29 rotates the neck 29 and sleeve 27 are also turned in a horizontal plane. Thus, a large tank can be readily washed. However, ordinarily the water issuing from the nozzles 31 would gradually increase the speed so that eventually there would issue a spray of water from the nozzles instead of a steady stream which is required. To avoid this difficulty, the hydraulic piston 42 in the cylinder 41 is provided and when the piston 42 moves to the top of the cylinder 41, this piston forces the fluid out through the tube 53, then through the valve 51 to the bottom of the cylinder 41 and when the piston moves downwardly, the fluid pass is reversed. As long as the valve 51 is open, the piston 42 reciprocates up and down freely, but by partially closing the valve 51 with the member 52, a braking action is applied to the piston 42 because of the fact that liquid will not be able to flow as freely through a hole of a fixed size with a set amount of pressure at a set temperature. This slowing down of the piston 42 therefore slows the speed of the beveled gear 34 which slows the entire unit. The tank 36 acts as a reserve tank for the cylinder 41 and the check valve 48 permits the fluid to flow from the tank 36 to the cylinder 41. The check valve 50 lets air into the reserve tank as the fluid is withdrawn therefrom. The hydraulic cylinder 41 together with the valve 51 can be adjusted to control the speed of the machine.

The ratchet arrangement shown in Figures 6 through 9 will, when being used, prevent the tank cleaning machine from revolving too fast. In this modified arrangement the intermeshing beveled gears are not used, and instead the roller 61 rides on the cam 63 and as the cam rotates with the nozzles 31, the roller 61 is moved in and out. This movement is transmitted through the linkage and shafts to the pawl 55 which moves the ratchet gear 54 so that the nozzles and cylinder move in a horizontal as well as a vertical plane.

We claim:

1. A tank cleaning machine comprising a stationary tube adapted to be connected to a source of supply of fluid, a rotatable sleeve arranged in

end to end relation with respect to said tube, there being diametrically opposed openings in said sleeve, a neck extending through said openings, interengaging means connecting said neck to said tube, said neck being provided with a plurality of apertures communicating with said sleeve, a pair of diametrically opposed nozzles extending from said neck, the lower end of said sleeve being provided with a tank for holding fluid, a cylinder arranged contiguous to said tank, a piston reciprocably arranged in said cylinder, a stem extending through said piston and cylinder and slidably mounted in said cylinder, a pin connecting the upper end of said stem to said interengaging means, a conduit connecting the lower end of 15 said cylinder to the lower end of said tank, a conduit connecting the lower and upper ends of said cylinder together, a valve arranged in said last named conduit, a bracket provided with a slot for receiving said pin, a block arranged below said 20 bracket and adapted to be connected to said stem, and rods having their lower ends connected to said block and their upper ends slidably engaging said bracket.

2. The apparatus as described in claim 1, wherein said interengaging means comprises intermeshing bevel gears.

3. The apparatus as described in claim 1, 5 wherein said interengaging means comprises a ratchet and cam.
